[57] **CLAIM**

The ornamental design for a telephone mounting bracket for hospital bed rail, as shown and described.

DESCRIPTION

FIG. 1 is a perspective view of a telephone mounting bracket for hospital bed rail, showing of my new design;
FIG. 2 is a front elevational view thereof;
FIG. 3 is a rear elevational view thereof;
FIG. 4 is a left-hand side elevational view thereof; and,
FIG. 5 is a top plan view thereof.

The broken line showing of a phone, phone cord, cradle, and bed rails in FIG. 4 is for illustrative purpose only.

The appearance of the right-hand side is a mirror image of that of the left-hand side.

The appearance of the bottom is the same as the top.
